Filed Feb. 27, 1963, Ser. No. 261,384
16 Claims. (Cl. 189—1)

The present invention relates to post-stressed continuous one-directional, two-directional and three-directional structural surfaces, and their assembly.

Whereas most known structural surfaces are dependent upon the primary use of compression as the mode in which induced load is propagated, the present invention is directed to the dispersion of an applied structural load over the structural span in terms of a geometric reduction of impetus by primary use of tension. As a result, longer span structures than have heretofore been considered feasible are rendered possible and economically practical. Although the present invention is contemplated as having one of its principal applications to long span structures, it is not intended to be limited to such applications. For purposes of illustrating the concept and structure of this invention, the herein described specific embodiment is a hemispherical dome structure. However, the invention is equally applicable to other shapes, such as arcuate surfaces, arches, flat surfaces, and compound and complex curvatures of practically any desired design.

The structural surface of the present invention may be considered to be a system formed of two networks, the first network being compressional in mechanical function with the second network being counterpoised as a tensional function, the two networks being interconnected and interrelated in force reactive relationship in such a counterpoised manner as to distribute a load over the structural span primarily in terms of tension. To this end, the compression network is comprised of a plurality of interconnected polygonal cells forming a continuous spinal structure over the extent of the span. A plurality of tension rods are interposed in a counterpoised manner with each polygonal cell. The tension rods of each cell are joined together at the centrum of the cell, and radiate therefrom to the perimeter or bounds of the cell, where they are fastened at their respective positions in a manner as to restrain the cells from bulging or buckling outwardly from the center as would be the normal tendency under compressive load. The assembled series of interrelated tension rods thus form the counterpoised tension network. The spinal compression network structure when completed includes means for post-stressing the cells into compression by a determined amount, and placing the tension rods in tension, thereby raising the resonant quality of the structure, and improving its response rate, and effectively distributing the structural load over the span primarily by means of tension. Accordingly, the load is carried primarily by the tension rods and not the compression network.

It is therefore one object of the present invention to provide post-stressed continuous one-directional, two-directional and three-directional structural surfaces.

Another object of the present invention is to provide for the dispersion of an applied structural load over a structural span in terms of a geometric reduction of impetus by primary use of tension.

Another object of the present invention is to provide a structural span comprised of interreactive compression and tension networks, wherein the structural load is primarily carried by the tension network.

Another object of the present invention is to provide a spinal structural span comprised of inter-connected polygonal cells, wherein the structural forces on said spinal structure are converted from compression forces to tension forces.

2

Other objects and advantages of the present invention will become apparent to those skilled in the art from a consideration of the following description of one exemplary specific embodiment of the present invention, had 5 in conjunction with the accompanying drawings, in which like reference characters refer to like or corresponding parts, and wherein:

FIG. 1 is a schematic top plan view of a hemispherical structural surface embodying the present invention;

10 FIG. 2A is an exploded perspective view, and FIG. 2B is an assembled perspective view, of a vertex cluster of polygonal cell walls, being enlarged detailed views of the portion of FIG. 1 encircled in dotted lines and labeled FIG. 2;

15 FIG. 3A is an exploded perspective view, but FIG. 3B is an assembled sectional view, of a central tension rod clamp or clevis and a tension rod cluster associated therewith, being enlarged detailed views of the portion of FIG. 1 encircled in dotted lines and labeled FIG. 3;

20 FIG. 4A is an exploded perspective view, and FIG. 4B is an assembled sectional view, of an assembly of a cell wall and associated tension rods, being enlarged detailed views of the portion of FIG. 1 encircled in dotted lines and labeled FIG. 4;

25 FIG. 5 is an enlarged detailed plan view of that portion of the structure schematically shown in FIG. 1 and included within the dotted lines labeled FIG. 5; and

FIG. 6 is a cross sectional view of the structure shown in FIG. 5, and taken along the line 6—6.

30 The two systems or networks of the structural surface of the present invention are indicated in the schematic hemisphere of FIG. 1. The compression system of polygonal cells is there designated by heavy lines, while the tension system is indicated by light lines. The compression system comprises a spinal structure of equilateral triangular cells 12 formed by bounding panels 10, joined at their vertices 11. An assembly of three tension rods 14 is associated with each cell 12, and comprises a clamp or clevis 13 located in the center of the respective cell,

35 which secures the ends of the three tension rods 14. Each tension rod passes from the center clamp to the center of a respective panel 10, thence through the panel, and mounts an abutment to the panel on the far side thereof, in a manner to restrain the panel from buckling outwardly

40 away from the central clamp 13 of the particular tension rod, but leaving the panel free to buckle in the opposite direction, toward said central clamp, by sliding over the tension rod and away from the abutment. However, since each bounding panel 10 of each cell 12 is common to the

45 adjacent cells (except of course the terminal walls of terminal cells of the structure), and since each cell 12 is provided with a central clamp 13 and associated tension rods 14 coupled to respective bounding panels 10, the buckling of a panel either inwardly or outwardly relative to a given central clamp is restrained by tensioning one or the other of the two rods 14 in opposing abutment therewith.

Thus it will be generally appreciated that with a structural system as illustrated in FIG. 1, the structural compressional load imposed upon the cell panels 10 stresses them in a manner to compress the area bounded by each cell 12, and causes the triangle bounding walls 10 to tend to buckle or curve toward a circular configuration. However, this compressional force is taken up in the tension rods 14 which restrain the cell panels 12 from buckling.

Accordingly the load is transmitted and dispersed throughout the structure primarily by tension.

Considering the structure of the hemisphere of FIG. 1 in detail, reference is had primarily to the enlarged fragmentary portion shown in FIGS. 5 and 6. The vertex assembly 11 is also particularly shown in specific detail in FIGS. 2A and 2B, and it comprises six clips 21. These

are assembled in radiating cluster fashion, as best shown in FIGS. 2A and B, with the ends of panels 10, one panel being seated between each adjacent pair of clips; and a bolt or other fastening means 21A secures each adjacent pair of clips 21 and interposed panel 10 to tie the cluster into an unitary structure. Each vertex 11 is assembled in this manner, thereby defining the complete spinal compression network.

The base 22 of the panel receiving sections of the clips 21 are formed at appropriate angles relative to the vertical axis of the structure to provide the desired curvature to the surface of the assembled structure. For this purpose, of course different clips 21 in any given cluster may be angled differently to afford the particular overall surface contour desired. Also, heels 23 of clips 21 are formed with flats so the cluster of cell vertices do not terminate at a point, but form hexagonal channels 24 adapted to receive the hexagonal pins 25. Pins 25 are designed to be equal or preferably slightly larger in cross section than the channels 24, and they are inserted after the structure is completed to post-stress the completed structure.

Post driving of pinion rods or pins 25 into channels 24 creates a predicted degree of inherent post-stress within the completed structural assembly, depending on the designed diameter of these rods. The pinion rods raise the resonant quality of the structural assembly and thereby improve its response rate to a desired degree. Where desired the pinion rods are designed to protrude beyond the interior and exterior surfaces of the completed spinal networks, providing threaded sections 28 to connect and bolt into place later placed cover plates, or batter plates, depending on the desired finished cross section of the finished shell. Thus these threaded rods or pins permit the spinal networks to act as their own falsework or scaffolding in the subsequent placement of laminate shells of a variety of materials. The number of laminar shells and their material are dependent on the intended function of the finished structure and the anticipated structural loads to be incurred. As an example, the basic spinal system may through the proper use of temporary batter plates be completely filled in by in situ foamed plastics, such as polyurethane or polystyrene and serving as a hollow core for a subsequently placed interior and/or exterior laminate of reinforced concrete. Thus, use of the pinion rods as plate connection enables the design engineer to: (1) save on excessive costs of falsework or scaffolding which is in most cases prohibitive in casting reinforced concrete in a warped surface; and (2) design the finished cross section of shell in several laminar layers, each laminate (a completed shell in itself) acts in juxtaposition with its counterpoised laminate. By this design concept full advantage can be taken of both the plate theory and the membrane theory in the design computations and the final design.

The central clamp structure 13 is shown in FIGS. 5, 3A and 3B. It is a three-way clevis formed of two halves 31 and 32 adapted to be bolted together by bolt 33. Each half has three sets of recesses 35A and B, 36A and B, and 37A and B adapted to be located opposite each other and to clamp the headed ends 34 of tension rods 14 therein, as shown in FIG. 3B.

Tension rods 14 radiate at 120° angles relative to each other from each central clamp 13, and pass through respective cell bounding panels 10, as shown in FIGS. 5, 6, 4A and 4B. Each cell panel wall 10 is provided with two holes 41 and 42, one located above the other at the mid-line of the panel wall. Bearing plates 43 and 44 are positioned on either side of wall 10 with holes matching and registering with those in panel wall 10. The tension rod 14 from the central clamp 13 of one cell formed by panel 10 passes through one set of registered holes, 41 for example, and is secured by means of nut 45, threaded onto the projecting end of the tension rod and bearing against the opposite side of panel 10. The tension rod

14 from the central clamp located in the other cell to which the particular panel 10 is common, passes through the other set of registered holes, 42 for example, and is secured by means of nut 46 threaded onto the projecting end of the tension rod and bearing against the other side of panel 10. It will be noted with particular reference to FIG. 4B that the rods 14 pass freely through their respective registered holes in wall 10 and bearing plates 43 and 44. Thus panel 10 is restrained against buckling or flexing toward the right in FIG. 4B solely by bearing on nut 46, while panel 10 is restrained against buckling or flexing toward the left in FIG. 4B solely by bearing on nut 45. Accordingly tension rods 14 are stressed only in tension and never in compression.

Since it is preferred that the tension rods 14 lie perpendicularly to their respective panels 10, and be affixed at the longitudinal midpoints of the walls, and that the central tension rod clamps be located in the center of their respective cells, the two tension rods associated with each panel 10 are displaced from each other perpendicularly to the longitudinal axis of the panel. Accordingly the central clamps 13 are correspondingly staggered in this manner, as best depicted in FIG. 6.

Thus, with the complete assembly of the described structural surface, comprising a complete spinal system of triangular cell 12, with the panels 10 of each cell centrally restrained by the tension rod system of three rods 14 radiating from a central clamp or clevis 13, the structural compression load on the spinal system is absorbed and distributed throughout the structure primarily by the tension rod system.

It is understood that the hemispherical structure utilized to illustrate the present invention is only for purposes of example, and that other surface shapes and contours might be formed with the present invention, requiring only that clips 21 be appropriately modified to orient the cells in the desired contour. Also, it will be appreciated that the triangularly shaped cells 12 are only for purposes of example; although this geometric shape is preferred, other polygonal shapes may be employed, accordingly changing the number of tension rods per cell. In each instance it is preferred that the number of tension rods in each cluster equal the number of sides to the polygonal cell, and it is further preferred that the clamp or clevis for these rods be located at the centrum of the cell, that the rods be connected to their respective cell panels at the midpoints thereof and perpendicularly thereto, and that the polygonal shape be a regular polygon.

In order best to effect the principles of the present invention it is preferred that the flexing cell panels 10 be designed to flex at an accumulation of about ten percent of the designed structural load. Under these conditions, ninety percent of the determined load will be supported by tension. Accordingly, the panels are contemplated as being of relatively light structural material, to take advantage of the more efficient use of the major structural components being in tension. Similarly the clips 21 act merely as lacings not ties, for the flexing panels, and therefore they too are of light gage structural material.

Having thus described one specific embodiment of the present invention for the purpose of facilitating an understanding thereof, it is understood that the invention is not limited to this embodiment, for numerous modifications and variations will be apparent to those skilled in the art. Accordingly such variations and modifications as are embraced by the spirit and scope of the appended claims are contemplated as within the purview of the present invention.

What is claimed is:

1. A structural surface, comprising a spinal network of interconnected flexing elements defining the bounding walls of polygonal cells, and a counterpoised tensional network therefor, comprising a system of tension elements intercoupled with each other, means coupling a

pair of tension elements to each of a plurality of said flexing elements, said coupling means including means for placing the elements of each of said pairs of tension elements in opposed tensional relationship to each other to restrain flexing of said flexing elements in opposite directions, said tension network including a tension circuit coupling one tension element of each of said pairs of tension elements to the other tension element of the pair externally of the flexing element to which such pair of tension elements is coupled.

2. A structural building unit comprising a polygonal cell having flexing elements defining the bounding edges of the cell, a plurality of tension elements radiating from a common connection within said cell to said flexing elements and extending through said flexing elements, and abutting means secured to said tension elements and abutting said flexing elements outside the cell, said tension elements extending through said flexing elements freely to permit flexing of said flexing elements toward said common connection, whereby said abutting means restrain said flexing elements from flexing outwardly from said common connection.

3. A structural building unit as set forth in claim 2, wherein said cell is a regular polygon, the number of tension elements equals the number of flexing elements with one tension element extending to each flexing element, said common connection is located in the centrum of said cell, and said tension elements extend through said flexing elements at the midpoints of the flexing elements.

4. A structural building unit comprising two contiguous polygonal cells having flexing elements defining the bounding edges of the cells and having one common flexing element defining one common bounding edge, each cell having a plurality of tension elements radiating from a common connection within such cell to the flexing elements thereof and extending therethrough, abutting means secured to said tension elements and abutting said flexing elements outside the respective cell, said tension elements extending through said flexing elements freely to permit flexing movement of said flexing elements toward the common connections of said tension elements, a tension element of each cell extending through said common flexing element, whereby said common flexing element is restrained against flexing outwardly from either of said common connections by its respective tension elements and the other tension elements restrain their respective flexing elements from flexing outwardly from their respective common connections.

5. A structural building unit as set forth in claim 4, wherein said cells are regular polygons, the number of tension elements of each cell equals the number of sides of the polygon with one tension element extending to each side, said common connections are located in the centrum of their respective cells, and said tension elements extend through said flexing elements at the midpoints of the flexing elements.

6. A structural surface, comprising a spinal network of interconnected flexing elements defining the bounding walls of a plurality of polygonal cells, adjacent cells having a common wall, a tension network for said cells comprising for each of said plurality of cells a plurality of tension rods radiating from a common connection within the cell to the flexing elements thereof and passing freely through said flexing elements to the outside of said cell, abutting means secured to each of the tension rods and abutting said flexing elements on the outside of said cell, whereby said abutting means restrain said flexing

elements from flexing outwardly relative to said common connection, the tension rods of at least some of the adjacent cells extending to common flexing elements therebetween to provide tension rod pairs for restraining flexing of said common flexing elements in two opposite directions, and said tension network providing a tension circuit coupling one tension rod of each of said pairs to the other tension rod of such pair externally of the flexing element to which said pair of tension rods is connected.

10 7. A structural surface, comprising a spinal network of interconnected flexing elements defining the bounding walls of a plurality of polygonal cells, adjacent cells having a common wall, a tension network for said cells comprising for each of said plurality of cells a plurality of tension rods radiating from a common connection within the cell to the flexing elements thereof and passing freely through said flexing elements to the outside of the cell, abutting means secured to each of the tension rods and abutting said flexing elements on the outside of the cell, whereby said abutting means restrains said flexing elements from flexing outwardly relative to said common connection, the tension rods of at least some of the adjacent cells extending to common flexing elements therebetween to provide tension rod pairs for restraining flexing of said common flexing elements in two opposite directions.

15 8. A structural surface as set forth in claim 7 wherein said polygonal cells are regular polygons.

20 9. A structural surface as set forth in claim 7, wherein the number of tension rods in each cell equals the number of sides of the cell.

25 10. A structural surface as set forth in claim 7, wherein said common connection is located in the centrum of the respective cell.

30 11. A structural surface as set forth in claim 7, wherein in said tension rods pass through the midpoints of the respective flexing elements.

35 12. A structural surface as set forth in claim 7, wherein said polygonal cells are regular polygons, the number of tension rods in each cell equals the number of sides of the cell, the common connection is located in the centrum of the respective cell, and the tension rods pass through the midpoints of the respective flexing elements orthogonally thereto.

40 13. A structural surface as set forth in claim 7, wherein in each flexing element common to two cells is restrained by a said tension rod pair.

45 14. A structural surface as set forth in claim 7, and further including means for assembling the ends of the flexing elements in clusters at the vertices of the cells.

50 15. A structural surface as set forth in claim 14, and further including means for forcing said clusters radially apart at said apices to post-stress the structural surface.

55 16. A structural surface as set forth in claim 7, and further including a covering skin carried by the structural surface.
